UNITED STATES PATENT OFFICE.

WILLIAM GRUS, JR., OF CHICAGO, ILLINOIS.

SPRING-LEAF LUBRICATOR.

1,189,057.

Specification of Letters Patent. Patented June 27, 1916.

Application filed January 14, 1916. Serial No. 72,023.

To all whom it may concern:

Be it known that I, WILLIAM GRUS, Jr., a citizen of the United States, residing at Chicago, in the county of Cook and State of Illinois, have invented certain new and useful Improvements in Spring-Leaf Lubricators, of which the following is a specification.

This invention relates to the lubrication of automobile spring leaves and the like, and differs from other constructions for this purpose, by introducing the lubricant from both edges of the leaves.

The principal object of the invention, is to provide a novel construction, combination and arrangement of parts for accomplishing this result.

In the drawings,—Figure 1, is a side elevation of a portion of a spring to which a lubricator of this class is attached. Fig. 2, is a sectional view on the line 2—2 of Fig. 1. Fig. 3, is a perspective of the distributor pan; and Fig. 4 is a perspective of the lubricator pad.

It is found under some conditions, that a more satisfactory lubrication of the leaves of a spring may be effected, by introducing the lubricant from both edges of the spring, and the present invention provides a novel and simple construction for accomplishing this result.

In the accompanying drawings, a leaf spring of the class to which this invention is applied, comprises a plurality of leaves 5 of the same size, placed one over the other, so that their edges are in substantial alignment. A casing 6, is formed with depending sides 7, which fit closely over the spring and extend below the lower edge thereof. The casing is preferably rounded at its edges, so that it fits smoothly over the spring, and in each of the depending portions, is a pad 8 of compressible material, such as felt, leather, or the like, in which a slot 9 is cut for forming a space in communication with a portion of the edges of the leaves within the casing. A perforation 10, is also formed in each pad 8, and corresponding perforations 11, are provided in the depending portions 7 of the casing, through which a bolt 12, is inserted below the spring with a nut 13 and washer 14, at the threaded end, for binding the pads 8 tightly against the edges of the leaves and for holding the casing on the spring.

A pan 15, is inserted in the casing on top of the spring and is preferably formed with

upstanding edges 16, which are slit in opposite sides forming tongues 17, which extend into the slots 9 of the pads 8. The center of this pan is preferably raised, so that the lubricant deposited therein will flow through the openings into the spaces formed by the slots 9. An oil cup 18, of any suitable construction, is threaded into the top of the casing and communicates directly with the pan 15, so that the lubricant inserted through the oil cup, falls directly upon the pan 15, and is thereby distributed or diverted to the edges of the spring, where the lubricant will enter between the leaves by reason of its capillary attraction and the sliding movement of the leaves with respect to each other.

The upper edges of the opposite sides of the pan 15, are preferably bent over at 18, so that they may be placed above the felt pads 8, thereby holding the pan in place, and preventing it from rattling in the casing 6, since the pads 8, are compressible against it. The tongues 17, also serve to keep the slots 9, of the pads 8, open at their upper ends, thereby preventing the space formed by the slots in the pads from becoming clogged.

While I have illustrated and described the preferred form of my invention, I do not desire to be limited to the exact details set forth, but, desire to avail myself of such variations and changes as come within the scope of the appended claims.

I claim:

1. The combination with a spring comprising a plurality of leaves, of a casing extending over the top and below the bottom at each side thereof, a compressible pad with a slot therein disposed in the casing at each side of the spring forming a space for confining a body of lubricant against a portion of the edges of the spring, a pan at the top of the spring having openings at the sides communicating with a slot in the said pad, fastening means for connecting the lower ends of the casing below the spring and for holding the casing in place, and an oil cup at the top of the casing for discharging the lubricant into the said pan.

2. In a leaf spring lubricator, the combination with a casing adapted to fit over a spring and down over the edges thereof; means insertible in either side of the casing to confine a body of lubricant against a portion of the edges of the leaves; and a pan insertible in the casing at the top thereof having overhanging edges engaged between

the tops of said means and the casing for holding the pan in position and preventing it from rattling.

3. In a leaf spring lubricator, the combination with a casing adapted to fit over the top of a spring and down along the sides thereof; pads insertible in the side portions of the casing each formed with a slot extending upwardly from the lowermost leaf and in communication with a portion of the edges of the leaves; a pan insertible in the casing having tongues extending into the slots of the said pads to hold the slots open and in

communication with the said pan; and means for admitting a lubricant through the casing to the pan so that it flows to opposite sides thereof. 15

In testimony whereof I have signed my name to this specification, in the presence of two subscribing witnesses, on this 10th day 20 of January, A. D. 1916.

WILLIAM GRUS, Jr.
